STEAK PLATTER

Herbert R. Carpenter, Chicago, Ill., assignor to Club Aluminum Products Company, La Grange Park, Ill., a corporation of Illinois

Filed Nov. 1, 1961, Ser. No. 67,334

Term of patent 14 years

(Cl. D44—10)

FIG. 2 is a bottom plan view;

FIG. 3 is an elevational view, partly in section, taken on line 3—3 of FIG. 1;

FIG. 4 is a fragmentary view on an enlarged scale of a portion of the steak platter side as viewed in elevation; and

FIG. 5 is a sectional view on the line 5—5 of FIG. 4.

I claim:

The ornamental design for a steak platter, substantially as shown and described.
